UNITED STATES PATENT OFFICE.

JOHN ISAAC THORNYCROFT, OF ISLE OF WIGHT, ENGLAND.

DRAWING-BOARD.

1,316,931.

Specification of Letters Patent. Patented Sept. 23, 1919.

Application filed March 4, 1919. Serial No. 280,537.

To all whom it may concern:

Be it known that I, Sir JOHN ISAAC THORNYCROFT, F. R. S., a subject of the King of Great Britain and Ireland, residing at Isle of Wight, England, have invented Improvements in or Relating to Drawing-Boards, of which the following is a specification.

It is often desirable to be able to remove a drawing from a drawing board to which it is attached and again replace it in exactly the same position on the board.

For instance, when a new design for an engine, ship, or other apparatus, object or structure has to be worked out by a draftsman, it is usual to have several sheets of drawings in hand that are worked upon alternately. The common practice in such cases is to employ separate drawing boards for the several sheets of drawings. If, however the several sheets of drawings would each be secured in turn to a single drawing board, for work to be done upon it, and after removal, be capable of being replaced upon the board and secured in exactly the same position in which it was previously secured, the use of several drawing boards would be unnecessary. This however cannot be easily and quickly effected with any certainty when ordinary drawing pins are used to secure the sheets of drawings in place on a board.

Now the present invention has for its object to overcome this difficulty.

For this purpose, a drawing board is provided at a suitable part thereof, conveniently near its top edge portion, with permanently attached pins or studs that project upward to a small height above the surface of the board and are arranged at a suitable distance apart, and the sheets of drawing paper to be drawn upon are provided near their upper edges with similar accurately spaced and shaped holes so that the perforated portions of each sheet in turn can be slipped over the fixed studs and then be firmly secured in place by clip devices adapted to fit over the corresponding edge of the drawing board and the studs and clamp the sheet of paper securely in place until it is desired to remove it when the clip devices can be easily and quickly removed

to admit of another sheet of drawing paper, provided with similarly spaced and shaped holes, taking its place. By these means, each sheet of paper can be easily and quickly secured in position, and after removal, can be easily and accurately replaced in its former position, as and when required, the one drawing board serving for use with any desired number of sheets of paper. Also, if desired, one or more sheets of more or less transparent material, for instance tracing paper or cloth, may be accurately placed one upon the other, or upon a sheet of drawing paper, and secured in place for comparison of different views or figures on the superposed sheets. Thus, when for example, it is desired to compare curves indicating different results or performances under different conditions, they can, when drawn on thin transparent or translucent material, for instance tracing paper, to the same scale, be easily and accurately superposed by placing the perforated sheets one upon the other and over the fixed studs and securing them in place on the drawing board by means of the clip devices, so that assuming the several figures to be drawn to the same scale, and that the base line and point of origin of each of them bear the same relation to the perforations in the sheets, they can be easily and accurately compared.

The studs are preferably of short cylindrical shape, and accurately spaced at a predetermined distance apart on the board and the holes in the sheets of paper are accurately cut and spaced to correspond. Sheets of drawing paper thus perforated can be easily suspended in any suitable box when not required for use.

In the accompanying drawings, Figure 1 is an elevation or face view of a drawing board embodying the invention, one of the holding clips being removed. Fig. 2 is a perspective view of such a clip, and Fig. 3 is a transverse section, corresponding to the line A B of Fig. 1, both Fig. 2 and Fig. 3 being drawn to a larger scale than said Fig. 1. Figs. 4 and 5 are similar views to Figs. 2 and 3 showing modifications.

In the example shown in Figs. 1, 2 and 3, two pairs of studs *a*, *b* are used, the studs

a, b of each pair being spaced a definite distance apart and secured to a small metal plate *c*, fixed as by screws, in a recess in the board *d* near its top edge, so that the studs 5 extend a short distance above the surface of the board, the two plates *c* with the pairs of studs being fixed to the board at a standard distance apart, or gage. The holes in the sheets of paper to be used with such a 10 board are formed exactly to the same gage. The drawing board *d* may advantageously be formed of a three ply panel, suitably framed, as such a board is less liable to warp and become untrue than a drawing board as ordinarily constructed.

e are perforated clips for holding the paper on the studs *a, b* and board *d* each formed of thin sheet metal of an elastic nature and bent to a more or less Ω shape 20 in cross section as shown, so as to be capable of being easily and quickly fitted in place over the top edge of the board *d* and removed as and when required, and so as to offer no obstruction, when in position, to the passage of a T square over them. The top edge and the back surface of the board is, or may advantageously be, recessed as at *f*, to receive the spring clips *e* so that the latter will not project beyond 25 the edge and back surface of the board and form obstructions.

When drawing boards and sheets of drawing paper of different sizes are provided for use, it will be advantageous to 30 provide all of the former with holding studs and all of the latter with perforations of standard gage and size.

Holding studs and clip devices according to the invention can be variously modified without departing from the essential features of the invention. Thus, the studs *a* and *b* instead of being carried by a plate secured in a recess in the front of the board, may as shown in Fig. 5, be carried by a 40 plate *c¹* fixed to the back of the board, and, preferably, in a recess therein, as shown, the studs extending through the board and projecting to a small extent from the front surface thereof. Also, the clip 45 devices instead of being formed with openings of round shape, as shown in Figs. 1, 2 and 3 to fit the studs, may be formed with openings in the form of open ended slots as shown in Fig. 4 to embrace the pins side- 50 wise and bear against the sheet of perforated paper engaged with the pins.

What I claim is:—

1. A drawing board having near the top edge thereof studs arranged at a distance apart and extending upward only to a 60 small height above the front surface of the board to enter and fit correspondingly arranged and shaped holes in a sheet of drawing material and clip devices each formed

of thin sheet material of an elastic character 65 bent to extend around the top edge of the board and embrace the back and front surfaces of the board, the thin front portions of the clip devices being formed with openings to receive the studs and arranged parallel to the front surface of the board so that when holding a sheet of drawing material in position on the board and over the studs, they will offer practically no obstruction to the passage of a T square over 70 them.

2. A drawing board having near the top edge thereof and at a distance apart, pairs of studs extending upward to only a small height above the front surface of the board 80 to receive and firmly hold in position a sheet of drawing paper having sets of perforations therein corresponding in position and diameter to the sets of studs, and clip devices formed of thin sheet material of an 85 elastic nature bent to extend around the top edges of the board and to embrace the back and front surfaces of the board, the front portions of the clip device being flat and parallel to the front surface of the 90 board and adapted to engage with the studs and when holding a sheet of drawing material in place on the board, being substantially flush with the free ends of the studs so that the fastening means will offer 95 practically no obstruction to the passage of a T square over them.

3. A drawing board having at each of a number of positions a recess in the back and a recess in one edge, bodily removable 100 clips each of thin sheet metal having a plane surface adapted to lie flat upon the face of the drawing board and also plane surfaces occupying one such back and edge recess and studs permanently attached to 105 the front of the board in the regions adapted to be covered by the front portions of the clips, said studs being of a length approximately equal to the thickness of said front portions of the clips and the latter 110 having openings therein to receive the studs, the whole being adapted to permit a pierced sheet of drawing material to be placed in position on the board, removed and replaced again in exactly the same position 115 and offering practically no obstruction to the manipulation of a T square over the board.

4. A drawing board having at each of a number of positions, a recess in the front, 120 a recess in the back and a recess in the edge and combined therewith means in the front recess having projecting parts adapted to receive a perforated sheet of paper, and a spring clip adapted to be received by recesses in the back and edge of the board and to engage the projecting parts of the means in the front recess. 125

5. A drawing board having at each of two widely separated positions along one edge, a recess in the front, a recess in the back and a recess in the edge and combined therewith, means in each front recess having a pair of projecting studs adapted to receive a correspondingly perforated sheet of paper, and spring clips each adapted to be received by a recess in the back and edge of the board and to engage the projecting 10 studs.
- Signed at Bembridge, Isle of Wight, England, this 3rd day of February, 1919.
- JOHN ISAAC THORNYCROFT.
